(57) **CLAIM**

The ornamental design for an opener with clip, as shown and described.

DESCRIPTION

FIG. 1 is a top perspective view of an opener with clip showing my new design;

FIG. 2 is a bottom perspective view thereof;

FIG. 3 is front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines showing the inside in FIGS. 3 and 4 are included for the purpose of showing portions that form no part of the claimed design.
